UNITED STATES PATENT OFFICE

DE FOREST Q. CRIMMINS, OF TONAWANDA, NEW YORK

AUTOMATIC PENCIL

Application filed May 30, 1930. Serial No. 457,652.

This invention relates to improvements in automatic pencils, and particularly to pencils of this sort provided with a magazine in which a plurality of leads are contained and from which the leads are propelled one after another through the tip of the pencil.

The objects of this invention are to provide an improved, simple and practical pencil of this sort of durable construction, and which will not readily get out of order; also to provide in a pencil of this kind an improved magazine constructed to hold a number of leads so that one lead after another can be fed from the magazine as they become used up, and in which the leads are maintained in an orderly series so that the leads can be propelled without interfering with one another; also to construct a pencil having a magazine of open or skeleton form so that broken leads can be readily removed therefrom without removing or disturbing the unbroken leads; also to provide a magazine of this sort with an adjustable part which can be moved to one position to permit the leads to be inserted into the magazine, and which can be moved to a second position to prevent the leads from falling out of the magazine after the latter has been loaded; also to construct a magazine of this kind having a central slotted guide tube, and means of novel construction for automatically and successively feeding the leads thereto as the leads in the tube become used; also to provide a magazine with a movable follower which is normally held out of operative relation to the guide tube, and which when the last lead has been fed into the latter is automatically moved into the slot in the tube to hold said last lead therein; and also to otherwise improve the magazines of automatic pencils.

Other objects of this invention are to construct an automatic pencil having a plunger movable into the guide tube of the magazine for propelling the leads therethrough, and which is constructed and operated in a novel manner; also to provide means under the control of the user for actuating the plunger to feed the lead as required for use, and novel means for quickly returning the plunger to

its initial position when a lead in the magazine is used; also to provide in a pencil of this sort, a movable head or block operatively connected to the plunger, and a guide for said head and means for moving said head into operative relation to the guide at one end thereof, and out of operative relation thereto at the other end, whereby said head and its attached plunger can be moved from an initial position under the control of the user, in a direction to propel the lead for use, and whereby the plunger is returned quickly in an opposite direction to its initial position; and also to construct a pencil in which the aforementioned movements of the plunger and its attached head in opposite directions are effected by turning the operating knob or head of the pencil in one direction only.

Other objects are to improve and simplify the construction of automatic pencils in the other respects hereinafter set forth and claimed.

In the drawings:

Fig. 1 is a side elevation of an automatic pencil illustrating an embodiment of my invention;

Fig. 2 is a longitudinal sectional elevation thereof, on an enlarged scale, with a portion of the operating head broken away;

Fig. 3 is a side view of a rotatable sleeve for guiding the lead feeding plunger;

Fig. 4 is a similar view from the opposite side of the sleeve;

Fig. 5 is a longitudinal sectional view of the pencil, taken approximately on the line 5—5 of Fig. 2;

Fig. 6 is a fragmentary longitudinal section, on an enlarged scale, showing one position of the lead feeding plunger and its movable head;

Fig. 7 is a similar view, showing the plunger and its said head in another position;

Fig. 8 is a transverse section of the pencil, on line 8—8, Fig. 6;

Fig. 9 is a similar view, taken approximately on line 9—9 of Fig. 7;

Fig. 10 is a side elevation of the magazine for the leads, removed from the pencil;

Fig. 11 is a fragmentary longitudinal sec-

tion of the magazine, partly broken away, showing how the leads are inserted;

Fig. 12 is a transverse section of the magazine, on line 12—12, Fig. 10, on an enlarged scale;

Fig. 13 is a similar view, showing the position of the parts when the last lead has been moved to operative position in the magazine guide tube;

Fig. 14 is a transverse section of the magazine, on line 14—14, Fig. 10, on an enlarged scale; and

Fig. 15 is a similar view, on line 15—15, Fig. 10.

In the embodiment of the invention shown in the drawings, my improved automatic pencil comprises an outer cylindrical shell or casing A open at its upper end 10 and having an integral pointed or tapered lower end 11 provided with the usual central, longitudinal passage 12, through which the lead is propelled, so that a portion thereof extends out of the passage for use.

Within the shell A and adjacent its lower, tapered end 11 is a magazine B, which is constructed to contain a plurality of leads α .

In rear of or above the magazine B, the pencil is provided with a longitudinally extending, centrally disposed plunger C operatively mounted in a cylindrical guide sleeve 14, for movement towards said tapered end 11 of the shell A, and which sleeve in turn is disposed within a cylindrical threaded feed tube or member 15, which fits loosely within the casing A with its lower end 16 abutting against the upper end 17 of the magazine B, and its upper, open end 18 adjacent the open end 10 of the shell A.

Preferably, the upper end of the guide sleeve 14 extends out of the open end 18 of the feed cylinder 15 and is threaded for the reception of a detachable intermediate cap 20, which, if desired, can be provided with an eraser 21, and extending over the cap 20 is an operating head or knob 22.

The threaded feed cylinder 15 may be stationarily but detachably secured to the outer shell A by a bayonet connection comprising a projection 23 on said cylinder which engages in an appropriately formed, angular slot 24 at the upper end of the shell A. The guide sleeve 14 can be turned within and relatively to said stationary feed cylinder 15 by any suitable means, such as the pin and slot connection 25, shown in Fig. 1, and which includes the inclined cam face 26. The arrangement of these parts is such that operative connection is provided between the knob 22 and the guide sleeve 14 for advancing the plunger C when the knob is turned in one direction, and which if the knob is turned the other way allows the knob to be freed from said guide sleeve so that the plunger will not be moved backwards.

Any other suitable connections affording

the necessary relative movements between the parts can, however, be provided for securing the feed cylinder 15 in stationary relation to the shell A, and for providing an operative connection between the operating knob 22 and the rotatable guide sleeve 14.

The magazine B for the leads α comprises a longitudinal, substantially cylindrical, or tubular member 30 provided at its upper and lower ends with enlarged circular disks or end walls 31 and 32 which, as shown in Figs. 2 and 5, are adapted to fit snugly within the shell A, being held in stationary operative relation to said shell by the engagement of the lower disk 32 against a suitable stop, such as the large end of the tapered portion 11 and the engagement of the end of the feed cylinder 15 with the opposite end of the magazine and the retention, in turn, of the cylinder 15 and sleeve 14 in the shell A by the parts 20 and 22.

The tubular body 30 of the magazine A is cut away, preferably at its opposite sides for nearly its entire length, so as to provide one or more relatively large openings 34 leaving, however, adjacent the end disks 31 and 32, substantially cylindrical flanges or portions 35 and 36 respectively, connected by longitudinal strips or parts 37. The upper end 17 of the magazine is in the form of an annular hub or boss projecting from the adjacent end disk 31.

Axially disposed within the body member 30 of the magazine B is a longitudinal guide tube 40 rotatably journaled in central apertures in the disks 31 and 32, and which is slotted or cut away between said disks at 41 to permit the tube to receive the leads α . The guide tube 40 extends downwardly for some distance below the disk 32 and is provided at a distance from the latter with a fixed nut or collar 44, while loosely surrounding said tube adjacent said disk 32 is a plate or member 45 which is stationarily but detachably secured to said disk 32 in any suitable manner for rotatable adjustment about said tube 40. This may be effected by forming said member 45 with a central square opening 46 into the corners of which extend projections 47 on the disk 32. A tension coil spring 48 surrounds the guide tube 40 between the nut 44 and the member 45 with its opposite ends respectively secured to these parts. The tension of the spring 48 is such as to urge the guide tube 40 to turn in the direction of the arrows in Figs. 12 and 13. The tension of this spring may be adjusted as desired by disconnecting the member 45 from the projections 47, turning it in the appropriate direction for changing the tension of the spring, and then replacing it. The member 45 is prevented from accidental detachment from the projections 47 by the pressure of the spring 48.

As shown, the guide tube 40 is provided with a pair of laterally extending curved

arms or deflecting members 50 disposed in spaced relation, with their free ends adjacent to the wall of the body member 30. One of the longitudinal strips or parts 37 of the magazine B is provided with an inwardly extending radial, fixed abutment 51, and as shown in the drawings, the magazine is provided with a pair of spaced, transverse arcuate members 53, which extend across one of the openings 34 and connect the strips 37. On each of these cross pieces 53 is secured a flexible spring member 55 which extends from the outer side thereof through a notch therein into the magazine and has its free end connected to and movably supports a longitudinally extending rod or follower 56.

One of the end flanges of the magazine, as, for example, the flange 35, is notched or cut away at 56a, see Figs. 11 and 14, so that the leads α can be inserted into the magazine by first extending one end of each lead within the other flange 36, and then letting the other end of the lead drop through said notch 56. When the necessary number of leads have been so inserted, the notch 56 can be closed by suitable means, such as an annular friction band or member 57 extending about the flange 35. This band is disposed in open position in Fig. 11, wherein a lead is shown as just entering the magazine, and in closed position in Fig. 14, where one of the ends of the band has been turned so as to extend across and close said notch 56.

In order to fill the magazine with leads, said magazine is held substantially horizontally in the hand, and the notch 56a is uncovered by appropriate adjustment of the band 57. The guide tube 40 is now rotated in a backward direction, that is, against the action of the tension spring 48, by grasping the nut 44 until the arms or deflecting members 50 are moved to a position in which a lead, inserted as described, can drop upon the inner side of said arms, and be guided thereby into the guide tube 40. The guide tube is turned backwards, and the successive leads are inserted, until the parts assume the position shown in Fig. 12, where the first lead is disposed in the guide tube 40 and the last lead of the series is engaging the abutment 51. In this position, the tension of the spring 48 causes the arms or deflecting members 50 to hold said last lead firmly against the abutment 51 by the pressure exerted thereon through the intervening leads. Consequently, if the first lead, that is, the lead in the guide tube, is used up or is otherwise removed, the tension of the spring 48 will turn the guide tube so that its slot 41 will face towards the next lead, which will then be guided into the guide tube 40 by the arms 50. It will thus be seen that the guide tube intermittently rotates or turns in the direction of the arrows towards the abutment 51, as each lead

is used up, thus permitting another lead to be guided thereinto by said arms 50. The leads which are not in use are, therefore, maintained in an orderly series near the wall of the member 30, where they hold one another in parallel relation, being successively deflected or guided to the center or axis of the magazine by the rotation of the guide tube 40 and the engagement of the leads by the arms 50.

Since the last lead of the series, that is, the one engaging the abutment 51, will have no other leads behind it to hold it in position in the guide tube when it has been fed thereto, the follower 56 is utilized for this purpose.

In the position of the parts shown in Fig. 12, this follower 56 is held in an inoperative position between the back face of the abutment 51 and the outer faces of the arms 50, but as the guide tube rotates in feeding the leads the arms 50 will eventually assume a position in which they extend over the outer side of the follower 56, and as the last lead is received in the guide tube 40, see Fig. 13, the arms 50 will engage the follower 56 and move it into the slot of the guide tube against said last lead, thus yieldingly but effectually holding this lead in position and preventing it from dropping laterally out of the guide tube.

As shown in the drawings, the plunger C comprises a longitudinally disposed cylindrical rod or member which, when in retracted position, is disposed so that its lower end extends through and is guided in registering apertures 60 centrally formed in the adjacent transverse end walls 61 and 16 of the guide 14 and feed cylinder 15 respectively. In this position, said lower end of the plunger C is at or in line with the upper open end of the guide tube 40 of the magazine B, but has not advanced to a position where it can engage a lead in said guide tube. The other end of the plunger C is movably connected to a head or block 64 disposed within the guide sleeve 14, and which is provided on one of its lateral faces with teeth or threaded portions 65 formed for engagement with the inner wall of the threaded feed cylinder 15. For permitting this engagement, the guide sleeve is provided with a narrow, longitudinally extending slot 66 terminating at its upper end in an enlarged opening 67 and at its lower end with a corresponding opening 68.

In the retracted position of the plunger C and its head or block, the latter is disposed in register with said enlargement 67 of the slot 66 and is held so as to extend partly therethrough with its teeth 65 engaging the thread of the cylinder 15, by a suitable cam or part 69 secured to the inner side of the guide sleeve 14 opposite the enlargement 65. This cam 69 engages an offset projection 68 on the adjacent face of the block 64. The opposite

side faces of the block 64 are cut away to form parallel grooves 64a, within which the edges of the narrow portion of the slot 66 are adapted to be received, so that upon manipulation of the operating knob 22 in the proper direction to rotate the guide sleeve 14, the head or block 64 and its attached plunger C will be advanced, and said grooves 64a will move into registration with the said edges of the slot 66 as the guide sleeve 14 is rotated, and the block and plunger will rotate with the guide sleeve. As the block 64 is advanced, the teeth 65 of said block will be maintained in operative relation to the feed cylinder 15 by the engagement of the grooves 64a with said slot. Thus, by continuing the manipulation of the operating knob 22 the plunger C will advance into and propel a lead α through the guide tube 40 of the magazine B until the rear end of this lead passes into that portion of the guide tube 40 which extends below the disk 32. This advance movement of the lead in the tube is such that the slot in the guide tube will be cleared for the reception of another lead. Means are, therefore, provided to quickly retract the plunger C from the guide tube to permit another lead to enter the latter, in the manner explained in connection with the description of the magazine B.

The means provided for this purpose comprises a tension coil spring 70 suitably attached at one end to the upper or rear end of the plunger head or block 64 and at its other end to a cross pin or part 71 mounted in the upper end of the guide sleeve 14, see Fig. 5.

As shown in Figs. 6, 8 and 9, the head 64 is formed with a lengthwise aperture 72 which, in the position of the parts shown in Figs. 5, 6 and 8, extends mainly to one side of the axis of the pencil and towards the slot 66. The rear or upper end of the plunger C is movably received in this aperture 72 and is connected to the block 64 by means of a fine wire or the like resilient member 74, which is bent intermediate of its ends to form a loop 75 which is connected to the adjacent end of the spring 70 and extends thence into the aperture 72 where the two portions of the wire pass laterally to the outer side faces of the head or block through holes 76, and continue thence, as shown in Figs. 5 and 6, to the lower end of the block, where they are extended around and secured to the end of the plunger.

When the block 64 is in its offset, advanced position, the wire 74 is bent laterally, as shown in Fig. 6, by reason of the fact that the holes 76 are at that time at one side of the axis of the pencil.

However, the continued advance of the block 64 towards the lower end of the pencil will eventually bring the block to a position where it will pass out of sliding contact with

the edges of the slot 66 and into the enlarged opening 68, and since, during the movement of the block to this position, the coil spring 70 has been extended, the block will now be drawn centrally within the guide sleeve 14 by the tendency of the spring wire 74 to straighten out to the position shown in Fig. 7 through the pull of the spring 70. Consequently, the block 64 will be disengaged from the feed cylinder 15, and since no resistance will now be offered to the pull of the spring 70, the latter will cause the block 64 and its attached plunger to snap quickly back through the guide sleeve 14 towards the upper end of the pencil. In this movement, the projection 68 of the block will encounter the cam 69 so that the block will be diverted from its central position outwardly through the enlargement 67 of the slot 66 and will again be placed into operative engagement with the feed cylinder 15.

The cam 69 is preferably made of resilient or spring metal, so that it can yield when engaged by said projection 68 so as to prevent the block or head 64 from binding between the cam and the inner side of the sleeve 14.

In order to prevent rotation of the block 64 after it has been freed from the guide slot 66, the sleeve 14 is provided, opposite the guide slot 66, with another guide slot 80 into which the projection 68 of the block moves as the latter is retracted into the guide sleeve 14 through the enlarged opening 68 at the lower end thereof. Thus, the block is held from turning during said retrograde movement by the engagement of the projection 68 in said slot 80.

Thus, it will be readily seen that the plunger C is alternately advanced and retracted by manipulation or rotation of the operating knob 22 in one direction, and in each advance movement the plunger enters the guide tube 40 of the magazine B and propels a lead therethrough, and each time the plunger is retracted, another lead automatically assumes its operative position in the guide tube ready for the next advance movement of the plunger. This procedure continues until all the leads have been used up, at which time the follower 56 will be positioned in the guide tube, and in order to prevent this follower from being moved endwise along the guide tube with possible injury to the follower and its supporting parts 55, the upper end of the follower is cut away or tapered, as shown at 81, Fig. 5. When, therefore, the end of the plunger C engages said beveled end 81 of the follower, the latter will be deflected out of the guide tube 40 if the advance movement of the plunger C is continued.

The automatic pencil described is practical and positive in operation, and the leads can be successively propelled out of the magazine, by the rotation of the operating knob in one direction.

Another advantage, making for compactness and simplicity, results from the fact that the operating parts of the pencil, such as the magazine B, feed cylinder 15, guide sleeve 14 and the plunger C and its connections are all inserted into the shell A from the open upper end thereof. Thus, no separate removable tip is required.

I claim as my invention:

- means acting to rotate said guide tube so as to cause its slot to approach said abutment and to face one after another of said leads as each lead in said tube is used, means on said 5 guide tube which turns therewith and diverts said leads successively through said slot into said tube, and a follower movably mounted in said magazine and which, when said last lead enters said guide tube, is engaged and moved 10 by said lead diverting means into said guide tube so as to bear against and hold said lead in place in said tube.
8. In an automatic pencil, a shell, a magazine disposed therein and which is of substantially cylindrical form closed at opposite ends by apertured parts and having its sides cut away to provide a relatively large lengthwise extending opening giving access to its 15 interior, a slotted guide tube for leads in said magazine and which is rotatably mounted in the apertures of said end parts, whereby a series of leads can be inserted one at a time into said magazine through said side opening so as to be arranged in regular order about said 20 guide tube with the first lead disposed in the latter, means carried by said guide tube for deflecting the leads successively into said tube through the slot therein, and means for turning said guide tube to cause its slot to face 25 toward the next succeeding lead each time a lead enters said tube, and broken leads being removable from said magazine through said side opening thereof without removing the other leads.
- 30 9. In an automatic pencil, a shell, a magazine for leads disposed therein and which is of substantially cylindrical form closed at opposite ends by apertured parts and having its sides cut away to provide a relatively large 35 lengthwise extending opening giving access to its interior, a slotted guide tube for leads in said magazine and which is rotatably mounted in the apertures of said end parts, a notch in one of said annular flanges which 40 permits leads to be inserted into said magazine by extending one end of each lead within the opposite annular flange and dropping the other end of the lead through said notch, means for closing said notch to prevent the 45 leads from dropping out of said magazine, and means for causing a succeeding lead to enter said guide tube through said slot thereof, each time a lead is used.
- 50 10. In an automatic pencil, a shell, a magazine stationarily disposed in said shell and having a slotted guide tube rotatably mounted therein, said magazine being adapted to receive and support leads in a substantially 55 stationary series extending about said guide tube, means for rotating said guide tube to successively receive one after another of said leads through the slot therein as the lead in the tube is used, a movable follower supported in said magazine, the relative disposition of 60 said guide tube to said follower being such 65 that as the last lead enters said tube, the slot in said tube will face towards said follower, means for moving said follower into said slot to retain said last lead in said guide tube, a plunger disposed in said shell at one end of 70 said magazine and which is movable endwise through said guide tube to propel the leads into writing position, and said follower having a cam at one end thereof which causes said follower to be diverted out of said guide tube 75 to prevent injury thereto when said cam is engaged by the end of said plunger.
11. In an automatic pencil, a shell, a guide tube therein for receiving a lead, a plunger movable endwise into said tube for propelling 80 the lead therethrough to writing position, a track in said shell, a head connected to said plunger, and which is slidably engageable with said track, means at one end of the latter for moving said head laterally 85 into engagement with said track, means for driving said head along said track to project said plunger into said track, and means for laterally disengaging said head from said track at the opposite end thereof and for 90 quickly returning the same to the first mentioned end of said track for withdrawing said plunger from said guide tube to permit the same to receive another lead.
12. In an automatic pencil, an outer elongated unitary shell open at one end and having its opposite end tapered and perforated for the passage of leads, a removable magazine for leads which is insertible into said shell through said open end and abuts against 95 a stop within the shell, a plunger for moving leads through said magazine, a guide sleeve therefor, a feed cylinder within which said sleeve is received, and which cylinder is insertible into said shell and abuts against 100 said magazine, and means releasably connected with the open end of said shell for holding said feed cylinder in operative position.
13. In an automatic pencil, an outer elongated unitary shell open at one end and having its opposite end tapered and perforated for the passage of leads, a removable magazine for leads which is insertible into said shell through said open end and abuts against 105 a stop within the shell, a removable feed cylinder stationarily mounted in said shell, a guide sleeve rotatably disposed within said cylinder, a plunger for moving leads through 110 said magazine extending lengthwise of and rotatable with said sleeve and having operative engagement with said feed cylinder, means detachably retaining said feed cylinder in said shell in abutting relation to said magazine, and means for removably retaining said guide sleeve in rotatable relation to said cylinder and said shell and for turning said sleeve to effect operative movement of said plunger.
14. In an automatic pencil, a shell, a mag- 115

azine for leads disposed in one end thereof, a stationary threaded feed member in said shell, a rotatable guide sleeve, a plunger for moving leads through said magazine and which is disposed in and rotatable with said guide sleeve and having a part extending through said sleeve and which moves endwise in an advance direction in operative engagement with said feed member for propelling leads, means for withdrawing said plunger part within said guide sleeve and out of engagement with said feed member at a predetermined point in said advance movement and for quickly retracting it, and means for returning said plunger into engagement with said feed member at the end of said return stroke.

15. In an automatic pencil, a shell, a magazine for leads disposed in one end thereof, a stationary threaded feed member in said shell, a rotatable guide sleeve, a plunger disposed axially of the pencil in said guide sleeve for moving leads through said magazine, a head, a yielding connection between said head and said plunger for permitting said head to be moved laterally of said axis without moving said plunger out of its axial position, said guide sleeve having a slot with enlarged openings at each end, means for projecting said head through one of said openings into engagement with said feed member to permit said head and plunger to be advanced into and guided along said slot by turning said sleeve, and means for withdrawing said head through said other opening into said sleeve and out of engagement with said feed member and for returning said head and plunger to a position in which it can be again projected through said first opening into engagement with said feed member.

16. In an automatic pencil, a shell, a magazine for leads disposed in one end thereof, a stationary threaded feed member in said shell, a rotatable guide sleeve, a plunger disposed axially of the pencil in said guide sleeve for moving leads through said magazine, a head, a yielding connection between said head and said plunger for permitting said head to be moved laterally of said axis without moving said plunger out of its axial position, said guide sleeve having a slot with enlarged openings at each end, said head being formed to extend in part out of said slot and into operative engagement with said feed cylinder, and said head having grooves for the reception of the edges of said slot to permit said head and plunger to be advanced by turning said sleeve, a spring attached to said head for withdrawing the same through one of said slot openings into said sleeve and for returning it to a position opposite the opening at the other end of said slot, and a cam positioned in said sleeve to intercept

through said last mentioned opening and again into engagement with said threaded cylinder.

17. In an automatic pencil, a shell, a magazine for leads disposed in one end thereof, a stationary threaded feed member in said shell, a rotatable guide sleeve, a plunger disposed axially of the pencil in said guide sleeve for moving leads through said magazine, a head, a yielding connection between said head and said plunger for permitting said head to be moved laterally of said axis without moving said plunger out of its axial position, said guide sleeve having a slot with enlarged openings at each end, said head being formed to extend in part out of said slot and into operative engagement with said feed cylinder, and said head having grooves for the reception of the edges of said slot to permit said head and plunger to be advanced by turning said sleeve, a spring attached to said head for withdrawing the same through one of said slot openings into said sleeve and for returning it to a position opposite the opening at the other end of said slot, a cam positioned in said sleeve to intercept said returning head and project it laterally through said last mentioned opening and again into engagement with said threaded cylinder, said cam being flexible so as to yield for preventing said head from binding between the same and said sleeve, and means with which said head moves into engagement when withdrawn into said sleeve and by which it is guided during its return movement to prevent said head from being turned out of operative relation to said guide slot.
